UNITED STATES PATENT OFFICE.

FRED C. BOYD, OF NEW HAVEN, AND ALBERT J. BARNES, OF WEST HAVEN, CONNECTICUT, ASSIGNORS TO THE FARADAY COMPANY, OF NEW HAVEN, CONNECTICUT, A CORPORATION.

ELECTRIC STOVE.

1,363,227.

Specification of Letters Patent.

Patented Dec. 28, 1920.

Application filed August 2, 1920. Serial No. 400,778.

To all whom it may concern:

Be it known that we, FRED C. BOYD and ALBERT J. BARNES, citizens of the United States, residing, respectively, at New Haven 5 and West Haven, in the county of New Haven and State of Connecticut, have invented a new and useful Improvement in Electric Stoves; and we do hereby declare the following, when taken in connection 10 with the accompanying drawings and the characters of reference marked thereon, to be a full, clear, and exact description of the same, and which said drawings constitute part of this application, and represent 15 sent, in—

Figure 1, a side view of an electric stove constructed in accordance with our invention and shown with the doors open.

Fig. 2, a similar view partly in central 20 vertical section, illustrating means for vertically adjusting and swinging the supporting plate.

Fig. 3, a top or plan view showing the doors in the open position and the plates 25 swung partly out of the drum.

This invention relates to an improvement in electric stoves adapted either for cooking or heating, and in which a resistance or heating coil is arranged transversely 30 so that heat below the coil may be utilized as well as heat above the coil. The object of this invention is to provide a stove adapted for domestic purposes with particular 35 facilities for utilizing the heat below the coil, and the invention consists in the construction and arrangement of parts as will be hereinafter described and particularly recited in the claims.

In carrying out our invention we provide 40 a base 5 provided with feet 6. Supported by the base is a drum 7 of sheet metal and resting upon the upper edge of the drum is a resistance coil frame 8 additionally supported by vertical braces 21, and containing 45 the usual transversely arranged coils 9, the coils being connected with supply wires 10 and 11 in the usual manner. Preferably and as shown the coils will be covered by a grill 12 forming a support for a cooking 50 utensil. The drum 7 is provided on one side with an opening, closed by doors 13 and 14. At one side of the base and preferably adjacent to the door 14 is a vertically

movable rod 15, provided with a finger-piece 16 and formed with annular grooves 17 more or less in number to receive the end 55 of a transversely arranged set-screw 18, and connected with the upper end of the rod 15 is a plate 19 which will swing in and out of the drum by turning the rod 15, and 60 which may be raised or lowered within the drum by means of the same rod and held in its desired position by the screw 18 yet always free to be swung out of the drum. The purpose of this swinging plate is two- 65 fold. First, when using the top of the stove for heating or cooking it is desirable to arrange a shield below the coil so that heat tending to pass downward will be deflected upward and this is accomplished by raising 70 the plate 19 upward closely adjacent to the underside of the coil.

Second, to permit the contents of a utensil, placed upon the plate within the drum, to be examined from time to time, that is 75 to say, a vessel 20 may be placed upon the plate 19, and swung into or out of the stove as occasion may require, and the plate may be raised or lowered according to the depth of the utensil, or the heat required for cooking. This stove permits of an oven being placed upon its top, which may be used for cooking or for additional radiating surface for other heating purposes.

We claim:

1. An electric stove comprising a base, a drum mounted thereon and provided with doors, a heating coil frame mounted upon the upper edge of the drum, a vertically adjustable rod mounted in the base, means for holding said rod against vertical movement and a transversely arranged plate connected with the upper end of said rod.

2. An electric stove comprising a base, a drum mounted thereon and provided with doors, a heating coil mounted upon the upper edge of the said drum, a rod mounted in the said base and adapted to be vertically adjusted therein and a plate secured to the upper end of said rod, and adapted to be swung into or out of said drum.

3. An electric stove comprising a base, a drum mounted thereon and provided with doors, a heating coil mounted upon the upper edge of the said drum, a vertically movable rod mounted in said base, a trans-

2
versely arranged screw adapted to support said rod in various positions of adjustment, a transversely arranged plate secured to the upper end of said rod and adapted to be raised and lowered by said rod and swung into or out of said drum.

In testimony whereof, we have signed this

specification in the presence of two subscribing witnesses.

FRED C. BOYD.
ALBERT J. BARNES.
